UNITED STATES PATENT OFFICE.

FIRM B. BYERS, OF WILLIAMSPORT, PENNSYLVANIA.

RAILROAD-RAIL HOLDER.

No. 855,755.

Specification of Letters Patent.

Patented June 4, 1907.

Application filed October 17, 1906. Serial No. 339,328.

To all whom it may concern:

Be it known that I, FIRM B. BYERS, a citizen of the United States, residing at Williamsport, in the county of Lycoming and State of Pennsylvania, have invented new and useful Improvements in Railroad-Rail Holders, of which the following is a specification.

The object of my invention is the provision of means for retaining the rails of a railroad track in their proper positions relative to the ties and to each other under all conditions of service.

The length of the rail commonly in use is approximately sixty feet. Attempts have been made to use rails of greater lengths, for example, eighty or one hundred feet, which in the hot season of the year under the action of high temperature have buckled drawing the spikes from the ties or bent sidewise and destroyed the alinement or parallelism of the two lines of rails constituting the track proper. The rails also or parts thereof under the same conditions are moved longitudinally, an action designated as "creeping." Likewise under the blows and impact of heavy locomotives and trains the rails relatively become displaced.

My invention primarily consists in means for holding the rails fixed in their true relative positions to the ties and to each other so that "creeping" is prevented and the buckling and bending or displacement obviated.

Further, it consists in certain novelties of construction and combinations of parts hereinafter set forth and claimed.

The accompanying drawing illustrates one example and a modification of the physical embodiment of the invention constructed according to the best modes I have so far devised for the practical application of the principle.

Figure 1 is a side view in elevation of a portion of a track showing the means for anchoring and holding the rail to the ties, the retaining plates in this instance being located approximately at the center of a long rail. Fig. 2 is a side view in elevation illustrating the retaining and anchoring means applied at the meeting ends of two separate track rails. Fig. 3 is a cross section of Fig. 1 taken between the ties. Fig. 4 illustrates a modification wherein the base of a plate has a curved in lieu of a horizontal surface for engaging the top surface of a tie.

Referring to the several figures, the nu-

meral 1 designates the track rail; 2, the flanged base thereof; 3, the web of a rail having holes therethrough; 4, the ties, which in this instance are of wood; 5, tie plates; 6, the web of the tie plates; 7, the base of the plate; 8, lugs downwardly projecting from the lower surface of the plates to a distance sufficient to engage the top side edge of a tie; 9, a longitudinal recess or seat in a plate to receive the flange at one side of the base of the rail; 10, holes in the plates; 11, bolts which are passed through the webs of the plates and the rails; 12, spikes, the heads of which engage the edges of the plates and the shanks thereof enter the body of the ties; and 13, in Fig. 4, a rounded or curved surface at the under surface of a tie plate which engages the top of a tie and prevents a movement of the rail and plates longitudinally of the tie.

The downwardly projecting lugs 8 are preferably angular in shape and have the surfaces 14, 15, inclined toward each other so as to meet and form an edge 16, as shown. The lugs are of such a number and so disposed that when the tie plates are bolted in place the upper side edges of the tie will be frictionally engaged by the inclined surfaces thereof. The length of the plates may be such as to extend over one, two or more ties, and a pair of lugs are to be provided for each tie whatever may be the length of the tie plates.

In Fig. 1 the tie plate are shown located at the center of the length of a rail. However, a plurality of plates may be provided for each rail intermediate of its ends, the number depending upon the length of the rail.

In Fig. 2 the tie plates are shown located at the adjacent ends of two rails, thus constituting joint plates.

From the foregoing description taken in connection with the drawings it becomes obvious that an efficient means has been provided for attaining the ends set forth as the object of the invention. Under changes of temperature the lugs 8 engaging the edges of two or more ties on opposite sides thereof will prevent the creeping of the rail, the ties being firmly embedded in the ground. Moreover, buckling of the rail also is prevented for such action can take place only when longitudinal movement of the rail is possible. Under the blows and impact of heavy locomotives and trains, especially

upon curves, the said lugs will prevent side movement of the rails and their displacement from normal parallel positions.

The ends of the rails at a joint are likewise held together when they tend to contract under the influence of low temperature.

While I have illustrated and described only one example of the physical embodiment of the invention other and similar means for performing the desired functions will not be regarded as substantial departures.

What I claim is:

1. The combination with a track rail, of a plurality of ties; and tie plates; said tie plates being provided at their under surfaces with a plurality of lugs with inclined surfaces which engage the opposite sides of a tie.
2. The combination with a track rail, of a plurality of ties; and tie plates located intermediate the ends of the rail; said plates being provided at their under surfaces with a plurality of lugs with inclined surfaces which engage the opposite sides of each tie; means being provided for securing the plates to the web of the rail and to the ties.
3. The combination with the adjacent

ends of two track rails, of a plurality of ties; and tie plates; said tie plates being provided with projecting lugs at their under surfaces which engage opposite sides of each tie, said ties being located at opposite sides of the ends of the two rails.

4. The combination with a track rail, of ties; and two tie plates; each of said plates having a longitudinal recess or groove to receive the flange at the base of the rail, and also a pair of downwardly projecting lugs with oppositely inclined surfaces, for the purpose specified.

5. The combination with a track rail, of ties; and two tie plates; each of said plates having a longitudinal recess or groove to receive the flanges at the base of a rail, a pair of downwardly projecting lugs and a curved surface 13 at the base where the plate engages the top surface of a tie.

In testimony whereof I affix my signature in presence of two witnesses.

FIRM B. BYERS.
